[57] CLAIM

The ornamental design for a shoe sole, as shown and described.

DESCRIPTION

FIG. 1 is a bottom plan view of a shoe sole showing our new design;

FIG. 2 is a right side elevational view thereof, the left side being substantially a mirror image thereto;

FIG. 3 is a top plan view thereof;

FIG. 4 is a front elevational view thereof; and

FIG. 5 is rear elevational view thereof.
